their Attorney.

UNITED STATES PATENT OFFICE.

AXEL OLSON AND ALFRED HAST, OF ST. PAUL, MINNESOTA; SAID HAST ASSIGNOR TO SAID OLSON.

DOOR ATTACHMENT.

Application filed April 17, 1922. Serial No. 554,311.

To all whom it may concern:

Be it known that we, AXEL OLSON and ALFRED HAST, subjects of the King of Sweden, residing at St. Paul, in the county 5 of Ramsey and State of Minnesota, have invented certain new and useful Improvements in Door Attachments, of which the following is a specification.

This invention relates to door attachments 10 for closing the opening between the floor and the door, and more particularly to that type of analogous devices which are controlled to be effective by the swinging movement of the door.

15 An object of the invention is to provide an auxiliary closure attachment for doors which may be constructed of slender thin light-weight members novelly and effectively arranged to render the device practical, cheap of manufacture and durable.

To this end the invention consists in the construction, combination and arrangement of parts hereinafter described and claimed.

In the accompanying drawings:

25 Figure 1, is a front elevation of the lower end of a door and door frame, showing our improved closure applied thereto.

Fig. 2, is a view of the edge of the door showing the invention mounted thereon.

30 Fig. 3, is a fragmentary front elevation of the closure plate raising and supporting mechanism.

Fig. 4, is an end view of same.

Fig. 5, is a perspective view of the closure 35 plate,

Fig. 6, is a sectional view on line 6—6 of Fig. 1, and

Fig. 7, is a detail view of the gear and shaft.

40 In the drawings, 1 designates the jamb members of a door frame, and 2 the door swingingly mounted in the door opening by means of hinges 3, of which one only is shown. The door is seated when closed in the vertical rabbet 4, which latter is formed in the outer corner of the jamb member, the door being shown flush with the outer face 5 of the jamb. The door is also provided with a suitable lock, such as 1' 45 having the usual operating handle 1'' and the spring pressed latch bar 1^a, normally extending from the edge of the door and connected with mechanism actuated by said handle when the latter is actuated to with-

draw the bar against stress of its spring, 55 said spring and mechanism not shown.

The invention comprises a closure plate 6, vertically slideable keepers or supports 7 for holding the plate flatly and slidably against the door, vertically disposed toothed 60 racks 8 located adjacent to and above the plate at opposite sides of the door, adjacent to the vertical edges thereof, and secured by means of the screws 8' thereon, a shaft 9 arranged parallel with the lower edge 1'' of 65 the door and extending over and beyond said racks, and beyond the edge of the door which carries the lock 1'. Secured to the shaft as by means of the screws 10 are the spur gears 11, which latter mesh with the 70 racks to cause the shaft to travel vertically in parallelism with the lower edge of the door and with the floor 12' immediately thereunder. Loosely enveloping that portion of the shaft extending between the gears is the 75 pipe 12, which is somewhat smaller in diameter exteriorly than the hubs 11' of the gears.

For the purpose of keeping the gears in proper meshing position relative to the racks and for guiding the plate 6, the keepers 7 are provided. These keepers are each preferably formed of strap metal of uniform width bent intermediate their ends to form an inverted U-shaped loop 13 standing at right angles to the face of the door. The keepers 80 extend at right angles to the pipe, the bend of the loops thereof being semi-circular to form a bearing or seat for the pipe so that the latter may rotate therein. The side members of the loop differ in length to permit the lower member 7' of the keeper to overlap the plate 6. On either side of the loop the keepers are perforated by the longitudinal slots 14 through which loosely extend the retaining screws 14', which latter 90 are screwed into the door body to permit the keepers to slide freely. Obviously, when the shaft is caused to be rotated, the gears in their travel over their respective racks, will move the shaft and the keepers vertically over the surface of the door. As shown in Figure 3, in dotted lines at 14'', the slots are of proper length to permit a little play when the lower edge of the plate rests upon the floor.

100 Centrally of its length the plate is formed with an extension 15, having at its upper edge a bead or sleeve 16 adapted to loosely

surround the pipe 12, said extension having a bifurcation 15' of proper width to freely receive the intermediate keeper 7 as shown in Figure 1. The plate is held positioned on the pipe by the central notch 15" which latter loosely receives the regular screw 14' of the keeper.

The end of the shaft which extends beyond the edge of the door is of reduced diameter 10 to form the shoulder 16' and the stub 16", said shoulder being flush with the edge of the door. Journaled at its lower extremity on said stub, is the upwardly extending collapsible knee 17, said knee comprising the lower shaft engaging member 17', pivoted on said stub, and the upper member 17", pivoted on the stub 18 which latter is parallel with the shaft 9. The stud is carried by a bracket 19 which is secured to the door 20 as by means of the screws 19'. The members of the knee converge toward the door and are pivotally connected by means of the pivot pin 20, so that when the closure plate is moved upward the knee will bend 25 and cause the joint thereof to pass an appreciable distance inwardly over the edge of the door (see Fig. 2). As the stub 16" and the stud 18 extend beyond the edge of the door, the joint of the knee upon closing the 30 door, will engage with the outer face of the jamb member 1 (Fig. 6) whereby the knee members will straighten out as shown in dotted lines in Fig. 2, and thereby cause the closure plate to seat upon the floor as shown 35 at the right in Figure 1.

For the purpose of holding the plate normally in raised position, the extensile coil spring 21 is provided, the latter being connected under stress to opposite ends of the knee.

In operation, a closing movement of the door will straighten the knee in opposition to the spring as stated in the foregoing, the door being held closed by the lock bar 1'. Upon releasing the lock bar the knee 17, under the influence of the spring 21, will automatically assist in opening the door in its bending out movement, causing the gears to simultaneously roll upwardly on their respective racks and thus raise the closure plate 6 vertically from the floor, the plate being guided by the keepers 7.

We claim:

1. In a structure of the class described, a combination with a door and the door frame therefor having a rabbet to receive the door, of vertically disposed toothed racks fixed in horizontal alinement on the door, a shaft, gears fixedly carried by said shaft in mesh 55 respectively with said racks, a closure plate supported by said shaft, keepers for guiding said shaft to hold said gears in mesh with said racks, said keepers mounted to slide to a predetermined degree to limit the upward 60 movement of said plate, and a collapsible

knee having means whereby to be yieldingly held in normal collapsed state, said knee being pivotally connected at its upper end to the door and at its lower end to said shaft, the joint of said knee being normally located over the outer edge of the door to engage with the door frame in a closing movement of the door to cause said knee to straighten out when the door is seated in the rabbet of the frame. 75

2. In a device of the class described, the combination with a door and door frame, said frame having a rabbet to receive the door, of a closure plate slidable upwardly from the floor, keepers loosely overlapping said plate and mounted on the door to slide vertically thereon, a horizontal shaft rotatably supported on said keepers and connected to said plate, a vertically disposed hinged knee having spring means whereby to be yieldingly held in normally bent state, said knee being pivotally connected at its lower end to said shaft and at the upper end to the door and located to bring its joint in contact with the door frame in a closing movement 90 of the door, to thereby straighten out said knee when the door is seated in said rabbet, and means including gears and racks in co-acting relation, operatively connecting the door to said shaft whereby the latter will move vertically in parallelism with the floor when said knee is actuated. 95

3. In a device of the class described, the combination with a door and door frame; of a closure plate adapted to extend below the door and engage the floor when the door is closed, supporting means carried by the door operatively connected to said plate, said supporting means including a plurality of racks secured to the door and a horizontal 100 shaft projecting at one end beyond the door and carrying gears in mesh with said racks, said shaft being effective responsive to an upward pull thereon to raise said plate in parallelism from the floor, and spring actuated means operatively connected to the projecting end of said shaft and door, said means including a hinged knee adapted to engage the door frame in the final closing 110 movement of the door to impart a lowering 115 movement to said closure plate.

4. In a device of the class described, to be attached to the face of a door, the combination of a shaft adapted to be arranged parallel to the floor, a closure plate hung on said shaft adapted to extend to the floor, mechanism adapted to connect said shaft to the face of the door for rendering said shaft vertically movable in parallelism with the floor, a link adapted to be pivoted on the door and to extend downwardly and inwardly beyond the face of the door, adjacent the edge thereof, a link pivoted to the lower end of said link adapted to extend downwardly to said shaft and having piv- 120 125 130

- otal connection therewith, and an extensible spring connected at its respective ends to said links at points remote from the pivotal connection between them.
5. In a device of the class described to be attached to a door, the combination of a hinged knee adapted to bend in a vertical plane at right angles to the face of the door and adapted to be pivoted at its upper end to the door adjacent the outer vertical edge thereof, the joint of the knee being normally located adjacently opposite the outer edge of the door, a spring adapted to yieldingly hold said knee bent, a shaft pivoted to 10 the lower end of said knee and adapted to be arranged parallel to the floor, and nor-

mally extending from side to side of the door, a closure plate adapted to extend from the floor to said shaft and having loose connection with the latter, a gear carried by 20 said shaft adjacent each end thereof, a rack for each gear normally secured to the door, a tube loosely surrounding said shaft between said gears, and keepers normally slidably mounted on the door to slide vertically 25 thereover while extending over said plate and tubing and revolvably supporting the latter.

In testimony whereof we affix our signatures.

AXEL OLSON.
ALFRED HAST.
